Abraham Goodman, New York, N. Y., assignor to Franklin Simon & Co., New York, N. Y.

Application November 17, 1949, Serial No. 6,088

Term of patent 3½ years

(Cl. D3—26)

To all whom it may concern:

It is known that I, Abraham Goodman, a citizen of the United States of America, residing at 408 E. 50th St., city of New York, county of New York, State of New York, have invented a new, original, and ornamental Design for a Dress, of which the following is a specification, reference being had to the accompanying drawing, forming a part hereof.

Fig. 1 is a front view of a dress, showing my new design.

Fig. 2 is a back view of the dress shown in Fig. 1.

Fig. 3 is a side view of the dress shown in Fig. 1 as seen from the left.

I claim:

The ornamental design for a dress, as shown.

ABRAHAM GOODMAN.
